TO WILLIS W. HESTER AND BALEY P. BELK, OF BOWLING GREEN, KENTUCKY.

ROCK-DRILL.

1,093,6386.

Specification of Letters Patent. Patented Mar. 21, 1912.

Application filed December 7, 1910. Serial No. 596,155.

To all whom it may concern:

Be it known that I, MARTIN E. THOMAS, a citizen of the United States, residing at Bowling Green, in the county of Warren and State of Kentucky, have invented a new and useful Rock-Drill, of which the following is a specification.

This invention has reference to improvements in rock drills, and more especially for the drilling of coal or other like comparatively soft material, and its object is to provide a readily removable and renewable head and cutters for a coal drill, whereby the twisted shanks of drills already in use may be utilized and the head may be readily changed from one shank to another where shanks of different lengths are used without the necessity of providing each shank with a head.

In the present invention there is provided a head of solid construction readily adapted to drill shanks already in use with a minimum of change in the structure of the shank, the change being of a character readily made by an ordinary blacksmith, while each head has a suitable set of rotary cutters in interacting relation, whereby a bore may be rapidly cut, and in case of the breakage or dulling of the cutters any one or all of them may be readily replaced by new sharp cutters, the operation requiring only a tool adapted to the removal of a bolt. The entire head, or, if desired, the cutters only, are readily transportable in an ordinary miner's kit. The head is utilized as a carrier for feeding wings designed to carry the cuttings or chippings of the cutters back to the conveyer twist of the drill shank.

The invention will be best understood from a consideration of the following detailed description taken in connection with the accompanying drawings forming a part of this specification, with the understanding, however, that while the showing of the drawings is that of a practical embodiment of the invention, the latter is not confined to the exact disclosure of the drawings, but may be variously modified without material departure from the salient features of the invention.

In the drawings:—Figure 1 is a side view of a drill with the head attached thereto. Fig. 2 is an end view of the head of the drill. Fig. 3 is a rear view of the head of

the drill detached from the shank of the drill and with the feeding sleeve omitted. Fig. 4 is a section on the line 4—4 of Fig. 2. Fig. 5 is a detail view of a portion of the head showing one of the cutters and its supporting lug in axial section. Fig. 6 is a view of the wing carrying sleeve as seen from a position at right angles to the showing of Fig. 1.

Referring to the drawings, there is shown a drill shank 1 which may be of the ordinary twisted type, and usually these drill shanks vary from two to six feet in length. There is provided a head 2 which may be a casting or forging of appropriate material formed at one end with an elongated socket 3 into which may be fitted a tapered end 4 of the shank 1, the socket being appropriately tapered to receive this tapered shank, and the socket and shank are provided with passages so located as to match when the shank is within the socket, and a pin 5 serves to secure the head 2 to the drill shank 1. This pin may be of any appropriate character, whether in the form of a plain pin or cotter pin, or a bolt, all of these fastening devices being commonly used for such purpose. The end of the head 2 remote from the socket 3 is formed with lugs 6 which in the instance shown are three in number and project in a general radial direction to the longitudinal axis of the head, and each lug is set at an angle to the longitudinal axis and to the cutting plane of the head and, also, at an angle to the other lugs, so that one end of each lug is directed forwardly and outwardly with reference to the direction of rotation about the longitudinal axis of the head. Each lug has opposite plane faces parallel one to the other and is provided with a perforation perpendicular to said faces for a bolt 7, the head of which confines a disk cutter 8 directly against the outer face of the lug, so that each cutter is presented to the material to be cut at an angle of about fifty-three degrees, although such angle is not mandatory, but is found in practice to answer the purpose of the invention. The body of the head 2 adjacent the rear face of each lug may be undercut as indicated at 9 to accommodate a nut 10 on the end of the respective bolt 7, but the depth of this undercut and its presence at all will depend upon the size of the drill head. The cutters 8 are shown as of cir-

cular form with curved faces merging into a peripheral edge constituting the cutting edge, and these cutters are mounted to turn upon their supporting bolts, so as to rotate 5 upon their individual axes during the operation of the drill and are also caused to traverse an orbital path about the longitudinal axis of the drill as a whole.

The planes of the cutting edges of the 10 several cutters are at such an angle one to the other that they will intersect at the central longitudinal axis of the cutter head if the latter be projected a short distance beyond the front edge of the cutter head in 15 the direction of travel of the cutter into the material being operated upon. With cutters disposed as shown in the drawings, their active portions will extend from the most advanced points in the direction of the longitudinal axis of the cutter head back to a point approximately at right angles to the forward portion of the cutter, so that the active cutting edge at any one time embraces nearly or quite ninety degrees of the circumference of the cutter. The cutter, therefore, 20 because of its large active extent works rapidly into such material as coal. At the same time, the lugs 6 and head 2 may be made massive enough to readily withstand all the 25 strains under which they may be placed in the operation of cutting, and will withstand any strains without breakage or distortion which will be withstood by the cutters themselves, or by the twisted shank of the drill 30 body. Moreover, since the projection of the shanks of the bolts beyond the lugs is only that of the thickness of the cutting disks, such bolts will readily withstand all strains to which they may be subjected without it 35 being necessary to make them unduly massive.

The socket portion 3 is made substantially square exteriorly and adapted to this square portion is a square sleeve 11 having formed 40 on opposite sides inclined wings 12, these wings being preferably so positioned as to extend diagonally across the corresponding face of the sleeve at an angle approximating the angle of the twisted portions of the drill 45 shank or body, and the pitch of these wings is in the same direction as the pitch of the twisted portions of the drill body, so that cuttings or chippings removed from the cutters 8 are caught by the wings 12 and conveyed into operative relation to the twisted 50 portion of the shank to be carried by the latter to the mouth of the bore and there discharged. The same pin 5 utilized to secure the drill head to the shank may be 55 made of sufficient length to extend through

65 matching holes in the sleeve 11 to thereby hold this sleeve to the exterior of the socket 3 against escape therefrom. There is no danger of shearing this pin since there is no relative movement between the taper portion 4 of the shank 1 and either the socket 3 or the sleeve 11, since these several parts may be made to fit quite snugly and their form will prevent any relative rotation about the 70 longitudinal axis of the drill.

75 In the adaptation of the present invention to drill shanks already in use wherein the head of the drill is usually made integral with the shank thereof after the manner of an ordinary auger, the taper end 4 may be 80 readily formed by a blacksmith and fitted to the socket 3. Where the invention is applied to new drill shanks, the integral head is omitted and the twisted body is supplied initially with a tapered end 4. The change 85 of the head from one drill shank to another, or the renewal of the cutters is readily brought about by the miner without the necessity of sending the drill to the repair shop and without the necessity of having the 90 several drills of different lengths each provided with a head individual thereto.

95 For all ordinary purposes three cutters disposed in a circular series at one hundred and twenty degrees apart will be found well 90 adapted for the purpose, but the invention is not necessarily confined to the number of cutters shown.

What is claimed is:—

A cutter head provided at its active end 95 with a circular series of integral and substantially radial lugs with opposite plane faces parallel one to the other and inclined to the longitudinal axis of the cutter head, the end of the cutter head remote from the 100 lugs being formed into a socket with the exterior walls substantially parallel with the longitudinal axis of the socket, rotatable cutting disks one for each lug and mounted on that face of the lug toward the active face 105 of the cutter head, the axis of rotation of the cutting disk being perpendicular to the corresponding face of the lug, and a sleeve provided with externally inclined material-directing wings and having an internal bore 110 conforming to the external form of the socket end of the cutter head.

In testimony, that I claim the foregoing as my own, I have hereto affixed my signature in the presence of two witnesses.

MARTIN E. THOMAS.
